UNITED STATES PATENT OFFICE.

WILLIAM J. ROCHE, OF MEADVILLE, PENNSYLVANIA, ASSIGNOR TO THE SPIRELLA COMPANY, OF MEADVILLE, PENNSYLVANIA, A CORPORATION OF PENNSYLVANIA.

GARMENT-STAY.

1,212,811.

Specification of Letters Patent. Patented Jan. 16, 1917.

Application filed June 22, 1914. Serial No. 846,588.

To all whom it may concern:

Be it known that I, WILLIAM J. ROCHE, a resident of Meadville, in the county of Crawford and State of Pennsylvania, have 5 invented a new and useful Improvement in Garment-Stays, of which the following is a specification.

This invention relates to wire garment stays and more particularly to corset stays.

10 The object of the invention is to provide a flexible wire stay which yields readily in all directions, in which the bending strains are distributed over a considerable length of wire so as to avoid crystallization and deterioration of the metal and prevent the stay from taking a permanent set, and particularly a stay which is stronger and more resilient than prior stays and offers more resistance to bending strains.

20 The invention comprises the stay herein-after described and claimed.

In the drawings, Figure 1 represents a face view of one form of stay embodying the invention; Fig. 2 is an edge view there- 25 of; Fig. 3 is a face view of another form of stay embodying the invention, and Figs. 4 and 5 are similar views of other modifications.

The stay shown in the drawings is formed 30 from wire, a single continuous wire 1 being shown, which is bent back and forth in sinuous form to form a series of oppositely disposed loops 2 lying along the edges of the stay and which are connected by trans- 35 verse intermediate portions or crossings 3.

These loops may be of any suitable form and may lie directly opposite each other as shown in Fig. 1, or, the loops along one edge may be in staggered relation to those 40 along the other edge, alternate loops along the opposite edges of the stay being progressively arranged, as in Figs. 3, 4 and 5. The loops may be of any suitable shape, but are preferably wide loops which include 45 a considerable length of wire. Each loop has the wire forming its closed outer end bent or deflected in the plane of the stay toward its center line, thereby forming a re-entrant loop 4 within each of the main edge

50 loops 2. The reentrant loops extend nearly to the central line of the stay and give each of the main loops four portions of wire extending transversely to the length of the stay. This arrangement is particularly effective in resisting flatwise bending strains

which are taken up largely by torsion in the crossing portions of the wire.

The crossing portions of the wire may be bent, kinked or deflected in any suitable manner, but preferably in the plane of the 60 stay as shown in the drawings. In Fig. 1 each of the crossing portions is bent or inclined intermediate its ends, as at 5, all of the crossing portions being bent in the same direction, so that the loops along the opposite edges of the stay lie substantially directly opposite each other. In Fig. 3, each crossing portion of the wire is bent or deflected in the plane of the stay to form a loop or convolution 5^a, all of the loops or 70 convolutions pointing toward the same end of the stay. In this arrangement, where the crossing portions are deflected first toward one end of the stay and then back again, the eyes or loops along opposite edges 75 of the stay are in staggered relation. In Fig. 4 each crossing portion of the wire is bent intermediate its ends to form an eye or convolution 5^b, there being a continuous row of said convolutions along the middle 80 line of the stay. In both of the forms shown in Figs. 3 and 4 the crossing portions of the wire are parallel to each other from edge to edge of the stay and in all forms described, the bends or kinks in the crossing 85 portions add materially to the length of the wire in the stay and therefore distribute bending strains over a greater length of the wire and reduce the liability of crystallization and breakage. 90

Fig. 5 shows an arrangement in which the crossing portions of the wire are substantially V-shaped, and the eyes or loops 2 along the opposite edges of the stay are inclined longitudinally of the stay in opposite directions. The same is true of the reentrant loops 4, so that the stay when viewed flatwise has the appearance of a herring bone or arrow. 95

Any of the stays described may have the 100 intermediate connecting portions or crossings 3 deflected from the normal flat plane of the stay to render the same concave in cross section, so as to stiffen the stay in the flatwise direction and increase its resistance 105 to bending stresses in one direction more than in the other.

What I claim is:—

1. A garment stay, comprising wire bent back and forth to form a series of loops 110

lying at the edges of the stay and connected by transverse portions or crossings, the wire at the closed ends of the loops along both edges of the stay being bent inwardly nearly 5 to the center line of the stay to form a re-entrant portion in each loop.

2. A garment stay, comprising wire bent back and forth to form a series of loops lying at the edges of the stay and connected 10 by transverse portions or crossings, the wire at the closed ends of the loops along both edges of the stay being bent inwardly nearly to the center line of the stay to form a re-entrant portion in each loop, the crossing 15 portions of the wire being bent or deflected in the plane of the stay toward its ends.

3. A garment stay, comprising wire bent

back and forth to form a series of loops lying at the edges of the stay and connected by transverse portions or crossings, the wire 20 at the closed ends of the loops along both edges of the stay being bent inwardly nearly to the center line of the stay to form a re-entrant portion in each loop, the crossing portions of the wire being bent or deflected 25 in the plane of the stay and lying substantially parallel to each other from edge to edge of the stay toward its ends.

In testimony whereof, I have hereunto set my hand.

WILLIAM J. ROCHE.
